TRAFFIC SIGNAL FOR MOTOR VEHICLES

Filed Jan. 4, 1923

UNITED STATES PATENT OFFICE.

DELL L. ALBRIGHT, OF HOLLYWOOD, CALIFORNIA.

TRAFFIC SIGNAL FOR MOTOR VEHICLES.

Application filed January 4, 1923. Serial No. 610,600.

To all whom it may concern:

Be it known that I, DELL L. ALBRIGHT, a citizen of the United States, residing at Hollywood, in the county of Los Angeles and State of California, have invented new and useful Improvements in Traffic Signals for Motor Vehicles, of which the following is a specification.

My present invention relates to a traffic signal for motor vehicles, or the like, it being a special object of my invention to provide, at moderate cost, a signal suitable for use at night.

It is a further object of my invention to provide a signal which shall constitute a unit suitable for separate manufacture and sale and capable of being easily applied to any motor vehicle provided with a light socket upon the dashboard thereof, or elsewhere within convenient reach.

It is a further object of my invention to provide a signal which can be quickly attached and detached from the vehicle and which can be worn by the driver or operative of any vehicle without inconvenience, and without constituting a hindrance to the free use of the hand of the operative in turning the steering wheel, or otherwise.

It is a further object of my invention to provide a traffic signal of the character referred to which may be easily assembled from constituent parts which are already obtainable as articles of commerce, and which are capable of being united by simple means, not requiring an extensive outlay for tools or materials, and not requiring unusual skill in the association of said parts.

Further objects of my invention will appear from the following description and the claims appended thereto, it being understood that parts of my invention may be independently used, and that various modifications may be made without departure from the spirit and scope of my invention as the same is indicated in said description and claims.

It is believed that the general character of my invention will be readily understood from the following description of a specific embodiment thereof taken in connection with the accompanying drawing, in which—

Figure 1 is a general view of my traffic signal as the same may be attached to the back of the hand of an operative and con-

nected by a flexible cord to any convenient light socket, such as a light socket in the dashboard of a motor vehicle.

Fig. 2 is an elevation of the device shown in Fig. 1, the ends of two fingers and the thumb of an operative being also shown.

Fig. 3 is a vertical section approximately on the line 3—3 of Fig. 2, no fingers being shown.

The form of my invention which I have chosen for specific illustration may be said to comprise an encircling element 1, adapted to be carried upon the front and second fingers of the operative, to which is connected an electric light socket 2, of a character now readily obtainable upon the market, this socket being adapted to receive an incandescent bulb 3. Upon the encircling element 1 I prefer to provide circuit closing means which may comprise a resilient arm 4, secured thereto but insulated therefrom as shown at 5. This circuit closing means may be connected with one wire of a flexible cord 6, the other wire of this cord being shown as led directly into the rear end of the socket 2. The encircling element 1 being of conductive material and being in conductive contact with the socket 2, it will be understood that upon such depression of the resilient arm 4 as to bring the terminal portion thereof into contact with the mentioned encircling element 1, current will pass from one wire of the flexible cord 6, which may be secured by a nut 7 and the bolt 8 passing through the arm 4 and the encircling element 1 and insulated from the latter. The current will then pass through the socket 2 into and through the filament within the bulb 3 and out through the other wire of the flexible cord 6.

It will be obvious that the mentioned bulb 3 may be of red or other colored glass, but I find it sometimes advantageous to employ a separate element such as a bull's-eye 9 of colored glass, and this element may be of ruby glass such as is now readily obtainable upon the market. When I use a bull's-eye, this may be secured in any convenient way, and I have shown it as secured by means of a metallic flange 10 and a wire 11 bent into conformity with the outline of the bull's-eye, and secured, as by soldering, to the socket 2, the flange being shown as fitting over the edge of the bull's-eye and secured to the wire

11 by means of extensions from said flange which encircle said wire and may be soldered thereto.

Even though its securing element may but 5 partially encircle a finger or fingers of a driver's hand, it is an important merit of my signalling device that it may be worn upon the back of the hand so that when the hand is extended in the manner to which every 10 operative of a machine becomes habituated, a mere depression of the arm 4 will cause a suitable signal to be given. I have shown the device as worn upon the index finger and the middle finger of the left hand, and when 15 so worn the device leaves the hand of the operative free for use upon the steering wheel or elsewhere, and the arm 14 is conveniently placed to be depressed by the thumb of the same hand. It will, however, 20 be understood that my signalling element may be worn upon a single finger and may also be adapted to be worn upon other fingers than those referred to and the contact means may be adapted to be depressed 25 in any convenient way, as by other digits than the thumb. The application of tape at 12, or elsewhere, is, of course, optional.

What I claim is:

1. In a traffic signal, a supporting means 30 attachable to the first and second fingers of an operator, an electric light socket supported by said means, a switch connected to the supporting means, adapted to be operated by the operator's thumb, a wire bent in 35 the form of a loop and having extended ends secured to the socket, a flange secured to the loop and a glass positioned therein over the end of the socket.
2. A traffic signal comprising in combina- 40 tion a securing element adapted to encircle a plurality of fingers of a hand, an electric

lamp socket attached to said securing element and positioned to extend parallel to the fingers, an electric bulb in the socket, a loop formed of wire having a pair of ends extending parallel to the socket, means securing said ends to the socket, a flange secured to the loop, a glass held in the flange away from the lamp whereby the light from the lamp may illuminate a person's hand and be 45 transmitted through the glass.

3. A traffic signal comprising a securing element adapted to encircle a plurality of fingers of a hand, an electric lamp socket secured to said securing element and positioned to be located parallel to the fingers, a lamp in said socket, a wire loop having a pair of projecting ends, the ends being secured to the socket, a concavo convex lens mounted on the loop and adapted to be 55 spaced from the lamp and from the hand, whereby the hand will be illuminated by the lamp and light will be projected through the lens.

4. A traffic signal comprising in combina- 60 tion a securing element adapted to encircle a plurality of fingers, an electric lamp socket secured thereto adapted to extend parallel to the fingers, a lamp in said socket, a wire loop having its ends bent parallel to the 65 socket and secured thereto, a flange secured to the loop, a concavo convex colored lens carried by the flange spaced from the lamp whereby the lamp may illuminate the hand and project rays through the lens and a 70 spring switch mounted on said securing element, said switch having a straight portion adapted to be pressed by the thumb to make 75 an electric contact.

In testimony whereof I have signed my name to this specification.

DELL L. ALBRIGHT.
